CLAP ARRESTER

William F. Zimmermann, Maplewood, N. J., assignor to Gould & Eberhardt, Newark, N. J., a corporation of New Jersey

Application February 8, 1936, Serial No. 62,979

6 Claims. (Cl. 90—54)

This invention relates to improvements in shaping machines and particularly to that part of the shaping machine known as the clapper box.

The clapper box of a shaper, supports the cutting tool at the forward end of the ram, and is usually made up of a plurality of relatively movable elements, one of which is hinged along its upper edge. The hinged member directly or indirectly supports the tool and is arranged in such manner that under normal conditions of operation the weight of the tool and tool post normally maintains the hinged member in a closed position, that is with its rear face abutting the front end of the shaper ram. As the ram moves forward on its cutting stroke and the tool engages the work, the parts are held still more firmly together.

The hinged feature of the clapper box functions at the end of the forward cutting stroke and during the return stroke of the ram, to permit the tool to elevate slightly as the tool was drawn back over the cut just made. This swinging or lagging action of the tool is essential in machines of this character in order that the cutting point of the tool does not score the work or be chipped off by being forcibly dragged over the work.

With the advent of the newer steels and alloys, came faster speeds and cutting operations. The progress in that direction has been rapid and far reaching, so much so that machine design and machining methods of only a few years back are now obsolete. Shapers once were but tool room machines, they must now be production machines cut in the general shop, and what was safe and good practice in shaper design only a short while ago, is dangerous or impossible now with the higher speeds of modern practice.

Heretofore, the conventional shapers had ram speeds up to 100 strokes a minute, and in some cases, 120 strokes a minute, and the clapper boxes performed their intended functions satisfactorily.

The today's production or manufacturing shapers must run at a speed giving 200 or more strokes a minute which is approximately 100% increase over the machine of yesterday. At such speeds of 3 or more strokes a second, the clapper boxes flapped excessively and did not return to their normal position of rest in time for the taking of the next stroke.

A primary object of the present invention is to eliminate excessive and undue flapping of the clapper box of shaping machines with the end

in view of rendering such machines eminently suitable and capable of performing normal or high speed operations.

Another object of the invention is to take the excess flap out of clapper boxes in a manner not interfering or hindering the manual swinging of the tool clear of the work piece whenever necessary as in cases when the machine is set up for side shaping. In this type of planing operation, the tool is fed vertically downwardly a given amount before each cut is started. At the end of each stroke the operator grasps the tool post and manually lifts it up until it clears the top of the piece so that the tool does not drag along the side of the work on its return stroke. This is not an unusual operation for a shaper, and the present invention is so constituted that such operations may be performed with the ease and rapidity as was done heretofore.

A further aim of this invention is to reduce the flapping of clapper boxes in a manner not adding appreciably to the cost of the machine nor in any way interfering with the action of the several movable parts of the ram head or with any auxiliary mechanism or special tools that may be mounted thereon from time to time.

In realizing the objects of the invention it is proposed to core out the under side of both members of the hinged clapper box so as to accommodate a small latch element. The latch element substantially fills the recess provided in the two hinged members and does not therefore take up any valuable space or interfere with the tool mounting or position in which it may be desired to adjust the tool head. The latch member is so designed that it normally functions to limit the extent of free swing of the clapper and insures that it is on its seat at the beginning of each cutting stroke. At times when it is desired to swing the tool manually the latch member is quickly rendered ineffective as an arrester, but not to the extent of offering any physical interference with any other normal function of the machine.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such

drawings, like characters of reference denote corresponding parts throughout all the views, of which:—

Figure 1 of the drawings is a view of a shaping machine embodying the present invention. Figs. 2 and 3 are enlarged front and side views of the tool head and forward portion of the ram. Fig. 4 is a view of a shaping machine set up for side planing.

10 Referring more particularly to Fig. 1 of the drawings, the shaping machine there illustrated comprises essentially a base 10, a standard 11 rising therefrom, a ram 12 reciprocably mounted in ways at the top portion thereof, and a table 13 15 which is vertically and laterally adjustable upon guide ways provided at the front of the standard.

A large rocker arm 14 adjustably pivoted at one end to the ram 12 and at its other end to the machine frame oscillates to and fro and thus 20 advances and retracts the tool T carried at the forward end. The rocker arm 14 is formed with a longitudinal slot 15 within which an adjustable pivot pin 16 operates. The pivot is radially adjustable on a large power driven bull gear 17, 25 the greater is the radius of swing of the pivot pin the greater is the stroke of reciprocation of the ram and conversely. The large gear wheel 17 is driven from an initial power shaft 18 through a primary speed change gear set A and a secondary speed change gear set B, the primary 30 set A, affording 4 relatively fine changes in speed, and the secondary set B affording 2 coarse changes, making a total of 8 different speeds to the ram.

35 Speed change levers 19 and 20 are provided for selectively effecting the speed changes, while lever 21 is provided for actuating a main power clutch 22. Disengagement of the clutch 22, stops all movements in the machine.

40 The work table 13 is laterally movable upon a vertically adjustable saddle member 23, by hand or power. The power movement may be effected from either of two sources, to wit, from the initial part of the ram drive through the quick 45 traverse mechanism indicated generally by the numeral 24, or through the feed mechanism 25 operated intermittently and in synchronism with the revolutions of the bull gear 17.

Both of the table drives 24 and 25 have a shaft 50 26 in common which transmits the movements through a reverser 27 to the table cross feed shaft 28. The lever 29 controls the direction of table movement and the lever 29a selects the rate, that is, the quick traverse movement or the 55 intermittent feed movement.

The tool T is held in a tool post *t* and is adjustable therein in the usual manner. The tool post *t*, in turn, is mounted in a clapper block 30 which is hinged along its upper edge to its 60 supplemental member 31. The member 31 is a bearing member and is pivoted at 32 to an adjustable slide 33 and normally clamped in place by a clamp screw 33a. The slide 33 is mounted for adjustment radially of a revolvable but normally stationary head 34 fitted to the forward end of the ram 12. By adjusting the relative 65 positions of the head 34 on the ram 12, the slide upon the head, the bearing block upon the slide, and the tool in the tool post, the tool may be given an infinite number of positions.

Assuming that the parts are positioned as illustrated in Fig. 1, the normal cycle of operation is as follows: The operator mounts a workpiece W upon the table 13, sets the tool T for the proper 70 cut, engages the power feed and starts the ma-

chine. The ram is thereby propelled forward and the tool removes a section of the workpiece. During the forward movement of the ram the table and work are held stationary, but on the return movement of the ram and before the next 5 stroke is started the table and workpiece are indexed laterally and when the next stroke starts the tool engages and removes a new section of the workpiece. This cycle is repeated again and again until the surface of the workpiece is planed off to the dimensions required. 10

Because of the hinged mounting of the tool post and block 30, these parts are permitted to swing forward about the pivot 36 on the return stroke, whereby the tool point may ride lightly 15 over the work upon its rearward movement. Were the tool not so mounted, its cutting edge would quickly be knocked off on the return stroke and the surface of the workpiece badly scored.

Heretofore, the speeds of the tool room shapers 20 were not fast enough to create any difficulty in the operation of the clapper box. However, the newer steels and alloys revolutionized machine manufacture and today shaping machines must operate in the range of 200 strokes per minute. 25

At a speed of faster than three strokes a second, the clapper boxes of shapers are flung violently into the air at each return stroke, and due to the inertia of the parts, the tool does not return to its seat in time for the next working 30 stroke. This condition is enhanced further by virtue of the fact that the return stroke of the ram is faster than the forward stroke, and this quick return leaves the clapper box fluttering in the air. 35

The purpose of the present invention is to overcome that condition with the end in view of rendering a clapper box device capable of high speed operation. Fig. 3 of the drawings illustrates a preferred means and method of accomplishing that end which comprises a latch member 37 located at the under side of the block 30 and bearing block 31. One end 38 of the latch extends up and locks behind the bearing block while the other end 39 extends forward and up, 45 into a recess 40 formed in the hinged block 30. The rear wall 41 of the recess 40 projects downwardly and forms an abutment wall spaced from the upright portion 39 of the latch. This spaced 50 relation allows a limited swinging movement of clapper 30 sufficient to accomplish its intended functions, and at the same time not allowing the clapper to be flung violently into space on the return stroke of the ram.

At high speeds, a clapper box so fitted merely 55 clicks at the end of each stroke, and the tool always is seated before the next working stroke starts.

Sometimes it is necessary for an operator to inspect the cutting point of the tool, which is 60 accomplished by swinging the clapper about its pivot until the operator has a clear view of the tool point. The present invention is so arranged as not to render such inspection impossible, and for that reason the latch 37 has a finger portion 65 42 which projects slightly forward to a position where it may be actuated. The upper surface of the finger tip portion is inclined in a direction automatically facilitating the closing of the box.

70 Preferably the latch 37 is made of spring steel, but it is apparent that, once its functions have been perceived, it may be a pivoted rigid element or it may assume any other design appropriate for the purpose.

A particular advantage of a spring latch is its 75

utter simplicity in formation and ease in adaptation to a clapper box. The location of the latch under the clapper utilizes otherwise wasted space and furthermore is at the point where it may 5 exercise greatest mechanical advantage over the inertia of the swinging parts.

Figure 4 of the drawings illustrates a set-up for a tooling operation commonly known as side shaping, that is, an operation on the side of the 10 workpiece. In the performance of that kind of an operation, the table cross feed is cut out and the table otherwise clamped against lateral shift. A side cutting tool is mounted in the tool post and the shaper ram moves to and fro as before, 15 but instead of the work feeding across the path of movement of the tool, there is a relative movement effected between the work and the tool vertically in the path of movement of the tool. In a conventional shaper such vertical movements 20 may be effected in two ways, one way being by operating a hand screw 43 which propels the head 33 and all parts carried thereby and another way being by placing a hand crank 44 on the shaft 45 and operating same to elevate the table. 25 Normally this relative feed movement between the tool and the work is effected before the start of each working stroke so that the tool on its forward movement engages a new section of the workpiece. Figure 4 illustrates a side shaping 30 operation in which the tool point is well below the upper surface of the workpiece and in such position the swinging feature of the clapper box is ineffective automatically to prevent breaking of the tool point or scoring of the side of the work- 35 piece. In the performance of such operations it is customary, therefore, for the operator to grasp the tool post *t* and swing the tool upwardly and out of the way of the work on the return stroke of the ram, and let it down again into its normal 40 operating position prior to the beginning of the next forward stroke. In performing shaping operations of this character the ram speed is, of course, considerably less than two hundred strokes per minute so that the operator can 45 manually control the movement of the tool.

The clap arresting mechanism herein disclosed does not interfere with or prevent such manual control of the tool post for the reason that a simple and effective means has been provided for 50 rendering the latch mechanism ineffective as long as desired. To accomplish that purpose a headed screw 46 is threaded into the under side of the bearing block 31 directly behind the latch element 37 and in line with an aperture 47 formed 55 in the latch element. Thus, by inserting a screw driver or other suitable tool through the opening 47 the screw 46 may be backed out a distance sufficient to engage the under side of the latch 37.

Further backing out of this screw retracts the 60 portion 39 of the latch from the recess 40 in the clapper block whereupon the latter may freely swing its full distance. In this manner the clap arresting means may be quickly rendered ineffective without removing any elements of the ma- 65 chine, and when so rendered ineffective does not interfere with the normal functioning of the clapper box or any of the parts associated or carried therewith. To restore the latch mechanism to the position wherein it checks the move- 70 ment of the clapper box, the screw means 47 is returned to its ineffective position, and the machine is again ready for high speed shaping operations.

Without further analysis, the foregoing will so 75 fully reveal the gist of this invention that others

can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims:—

Having thus revealed this invention, I claim as new and desire to secure the following combinations and elements, or equivalents thereof, by Letters Patent of the United States: 10

1. A clapper box for machine tools in which the inertia of the parts normally induces excessive swing of the clapper member, combining a bearing plate and a tool supporting member pivoted thereto and normally free to swing away from the bearing plate, one of said members having a recess formed therein at a point removed from said pivot; a non-extensible latch member carried by the other one of said members adapted to project into the said recess whereby said pivoted member is constrained against unlimited movement relative to said bearing plate; and manually operable means for rendering said latch member selectively effective and ineffective to prevent movement of said tool supporting member. 15 20 25

2. A clapper box for machine tools combining a bearing plate and a tool supporting member pivoted thereto and normally free to swing from a position wherein it is supported by the bearing plate to a position approximately 90 degrees therefrom, each of said members having a recess formed therein at a point removed from said pivot, a latch member supported in the recess in one of said members and adapted normally to project into the recess in the other of said members whereby said pivoted member is constrained against unlimited movement; manually operable means for withdrawing said latch member from said last mentioned recess thereby to permit full movement of said tool supporting member; and manually operable means for maintaining said latch member in a position ineffective to prevent movement of said tool supporting member. 30 35 40 45

3. A clapper box for a high speed shaping machine in which the speed of reciprocation of the shaper ram induces excessive flutter and clap of the box, comprising a bearing plate member, a clapper member pivoted at one of its ends to said plate and normally adapted to seat against said bearing plate, a tool holding member mounted upon said clapper member between said pivot and the free end of the clapper member, means normally operative to limit the extent of free movement of the clapper member about its pivot, including an element carried by the said bearing plate member having a lost motion connection with the said clapper member, said lost motion connection permitting a limited free movement of said clapper member relative to said plate member and positively restraining movement of said clapper member beyond said limited amount. 50 55 60

4. A clapper box for high speed shaping machine in which the speed of reciprocation of the shaper ram induces excessive flutter and clap of the box, comprising a bearing plate member; a clapper member pivoted at one of its ends to said plate and normally adapted to seat against said bearing plate; means normally operative to limit the movement of the clapper member about its pivot during the reciprocations of the ram comprising a spring latch element secured to one of said members and having a lost motion connec- 70 75

tion with the other of said members, said lost motion connection permitting relative free movement between said members of a limited amount; and means for rendering said latch member ineffective to restrain movement of said clapper member.

5. A clapper box for a high speed shaping machine in which the speed of reciprocation of the shaper ram induces excessive flutter and clap of the box, comprising a bearing plate member, a clapper member pivoted at one of its ends to said plate and normally adapted to seat against said bearing plate and to swing freely away therefrom at the end of the forward stroke of the shaper ram, a tool holding member mounted upon said clapper member between said pivot and the free end of the clapper member, guide means restraining lateral movement of the clapper member when the latter is seated upon the bearing plate, and means normally operative to limit the movement of the clapper member about its pivot including an element secured in fixed relation to

one of said members and having a lost motion connection with the other of said members, said lost motion connection permitting relative free swinging movement between said members to a limited amount and positively restraining movement between said members beyond said limited amount.

6. A clap arrester for a clapper box of a machine tool combining a bearing block member, a clapper block member pivotally mounted at one end to said bearing block and normally free to swing about said pivot, tool holding means carried by said clapper block member between said pivot and the free end of the member, and inelastic means spaced from the clapper block member an amount sufficient to permit the tool to clear the work and operative to engage the free end of said clapper block member to limit the free swing of said clapper member away from the said bearing block to a predetermined maximum. 20

WILLIAM F. ZIMMERMANN.
